UNITED STATES PATENT OFFICE.

KENWORTHY J. THOMPSON, OF MANSFIELD, OHIO.

ROLLING APPARATUS.

Application filed May 31, 1923. Serial No. 642,469.

To all whom it may concern:

Be it known that I, KENWORTHY J. THOMPSON, a subject of the King of Great Britain, and a resident of the city of Mansfield, in the county of Richland and State of Ohio, have invented certain new and useful Improvements in a Rolling Apparatus; and I do hereby declare that the following is a full, clear, and exact description of the same, reference being had to the accompanying drawings, and to the numerals of reference marked thereon, which form a part of this specification.

This invention relates to machines for compressing and rolling strips of fabric and the like.

In the manufacture of tires two or more ply fabric is employed and hitherto this has been made by pressing together the strips of rubberized fabric by hand with or without the aid of manually operated tools.

It has been found very difficult to expel all the air from between the strips and bring the layers of fabric into close contact with each other. This is necessary to prevent fabric separation during vulcanization.

Even a small air bubble will expand in the vulcanizing operation and prevent union of the two layers over a much larger area than that originally occupied by the bubble.

One of the principal objects of the present invention, therefore, is the provision of means for pressing together two or more treated strips of fabric so as to expel the air therebetween.

A further object of the invention is the provision of means for rolling an endless strip of fabric.

It is also an object of the invention to provide means for supporting an endless band of fabric in extended position and simultaneously passing it between rolls.

An additional object of the invention is to provide a rolling machine, into which an endless band can be readily inserted and as readily withdrawn.

Other and further important objects of this invention will be apparent from the disclosures in the specification and accompanying drawings.

On the drawings:

Figure 1 is a front elevation of a machine embodying the present improvements.

Figure 2 is a section on the line 2-2 of Figure 1.

Figure 3 is a side elevation of the machine.

Figure 4 is a section on the line 4-4 of Figure 1.

Figure 5 is an enlarged detail view of a part of the operating and locking mechanism.

Figure 6 is a section on the line 6-6 of Figure 3.

Figure 7 is a section on the line 7-7 of Figure 5.

Figure 8 is an enlarged detail view of the toggle mechanism for operating the tension roll.

Figure 9 is a view taken on the line 9-9 of Figure 6.

As shown on the drawings:

The machine comprises a base 10, from which, adjacent one corner, rises a standard 11. On one side of this standard is secured or made integral therewith a frame 12.

In the upper part of this frame is journaled a shaft 13 carrying a roll 14. Above this roll is a similar roll 15 carried by a frame 16 pivotally connected to the main frame at 17.

In view of the fact that the frame 16 is supported at one end only and the rolls 14 and 15 are separable at their ends opposite to the frame support, an endless strip of material may readily be inserted between 85 or withdrawn from the rolls.

The shaft 18, which carries the roll 15, is not journaled directly in the frame 16, but in bearings 19 having cylindrical extensions 20 which project into sockets in the frame 16. In these sockets are arranged springs 21 tending to press the roll 15 downwardly. The tension of these springs may be varied by means of headed bolts 22.

Instead of using springs to provide the desired downward pressure on the roll 15 fluid pressure, such as compressed air, may be employed. This may conveniently be accomplished by inserting compressed air connections in place of the bolts 22 and placing piston rings on the extensions 20.

The free end of the frame 16 is normally connected to the frame 12 by means of a hook 23, rotatably secured to the lower frame and adapted to engage a pin 24 projecting from the end of the frame 16.

When the hook 23 is disengaged from the pin 24, the frame 16 swings upwardly about its pivot not only as the result of the action of springs 21, which act on the roll 15, but

also by the action of springs 25 provided for this purpose near the pivotal axis of the frame. Pins 28 are provided for limiting the downward movement of the roll 15 when the frame 16 is elevated.

The hook 23 is rotatably mounted on an eccentric 26 secured to a shaft 27 journaled in the frame 12 so that by turning the shaft after the hook has been brought into engagement with the pin 24, the upper frame may be drawn downwardly. A handle 29 secured to the end of this shaft 27 enables it to be turned when desired.

On the strap around the eccentric 26, which carries the hook 23, pins 60 may be arranged for engagement with the handle 29 so that the handle 29 cannot be brought into vertical position without causing the hook to engage the pin 24 or into horizontal position without disengaging the hook from the pin.

In addition to providing a pair of spring-pressed rolls, it is also desirable to provide means for holding the endless band of treated fabric in extended position while it is being passed through these rolls, and also to provide means for examining the band while under rolling treatment.

For this purpose brackets 30 are provided, extending forwardly from the frame 12 and between them extends a table 31. At the forward edge of this table a roll 32 is pivotally mounted. This table 31 is so arranged that its upper surface is in substantially the same plane as the line of contact of the rolls 14 and 15 and the upper surface of the roll 32.

On the other side of the frame 12 another roll 33 is provided, rotatably mounted on a shaft 35 journaled between lugs 34. A tension roll 36 is provided, journaled between arms 37 secured to the shaft 35. By turning this shaft, therefore, the position of the tension roll may be varied. The mechanism for turning the shaft includes a sleeve 38 rotatably mounted on the shaft and provided at its outer end with a flange 39. The shaft 35 is provided with a similar flange 40. A bolt 41 attached to the flange 39 extends through an arcuate slot 42 in the flange 40. A wing-nut 43 serves to clamp the two flanges in any desired position.

On the sleeve 38 is an arm 44 connected by links 45 to an arm 46 attached to the shaft 27, which is rotatable by the handle 29. Hence, by operating the handle 29 the shaft 35 may be turned and the position of the tension roll varied.

The machine is intended for use on annular bands of various diameters, and in changing from one size to another size it is desirable to provide quick means for adjusting the relative positions of the flanges 39 and 40 so that when the handle 29 is brought into its upper position the tension roll is swung downwardly to the requisite extent.

For this purpose I may provide a series of steel bands having diameters equal to the band to be pressed.

To set the machine by one of these bands 61 the wing-nut 43 is loosened so that the flanges 39 and 40 are free to move relatively to each other. The handle 29 is placed in vertical position and the band 61 is placed around the rolls as shown in Figure 3. The tension roll 36 is then depressed until the band 61 is drawn tight. The wing-nut is then tightened to lock the flanges 39 and 40 together.

The handle 29 is then swung downwardly to raise the tension roll to allow the steel band 61 to be removed and the fabric band to be inserted in its place.

In place of, or in addition to, the use of steel bands of known diameter, a scale 62 may be provided behind one of the arms 37 which carries the tension roll 36. This scale may be graduated arbitrarily for use with a computing table or it may be graduated so as to give directly the circumference or diameter of a steel tape which, when stretched, will encircle the rolls with the tension roll 36 in that position.

It will be seen from Figure 8 that when the tension roll is extended downwardly the arm 46 and links 45 are in substantially a straight line so that we have a toggle joint connection.

While, in view of this toggle connection, direct pressure on the tension roll cannot turn the shafts 35 or 27, the parts might, unless otherwise prevented, become displaced by vibratory movements. To hold the handle releasably in the desired position, a bolt 47 is slidably mounted on the handle 29. This bolt is provided with a rounded end 48 adapted to enter an aperture in the upper frame 16. A knob 49 at its other end enables the bolt to be withdrawn manually against the action of its spring 50.

The lower roll 14 only is rotated by power, and for this purpose a pulley 51 is rotatably mounted upon the shaft 13, which carries this roll. A clutch 52 serves to connect the pulley to the shaft when desired. This clutch is operated by a bell crank 53, one arm of which is forked for engagement with a pin 54 on the clutch. The other arm of the bell-crank is connected by a link 55 to a pedal 56.

The operation is as follows:

The handle 29 is swung downwardly, and by engagement with one of the pins 60 the hook 23 is simultaneously disconnected from pin 24. The springs 25 tend to move the frame upwardly so as to separate the rolls 14 and 15 and allow the endless band to be inserted therebetween. The downward movement of the handle 29, by means of shaft 27, arm 46, link 45, arm 44, shaft 35 and arms 37, causes the tension roll 36 to be

moved upwardly, thereby enabling the band to be readily placed therearound.

The next step is to swing the handle 29 upwardly, and at the same time depress the frame 16 by hand to allow the hook 23 to engage the pin 24. This hook is preferably moved into engagement by hand, but may be forced into engagement with its pin by pressure of the handle against the pin 60 on the strap portion of the hook.

The machine is then set in operation by pressing down the pedal 56, which operates the clutch between the pulley 51 and the shaft 13, which carries the roll 14.

I am aware that numerous details of construction may be varied through a wide range without departing from the principles of this invention, and I therefore do not purpose limiting the patent granted otherwise than necessitated by the prior art.

I claim as my invention:

1. A machine of the kind described comprising a frame, a plurality of rolls supported thereby and adapted to carry an endless band in extended position, a support for said frame connected thereto adjacent one end of said rolls only, and a further roll movable as a whole relatively to the other rolls and adapted to press the band against one of such rolls.

2. A machine of the kind described comprising a frame, a plurality of rolls supported thereby and adapted to carry an endless band in endless and extended position, a support for said frame connected thereto adjacent one end of said rolls only, a second frame pivotally connected to the first frame adjacent said support, a roll carried by the second frame adapted to press the band against one of the first mentioned rolls and means for releasably connecting the free end of the second frame to the first frame.

3. A machine of the kind described comprising a lower frame, a roll journalled therein, a second frame pivotally secured to the first frame, a roll carried by the first frame adapted to press against the first roll, a tension roll supported by the lower frame and means for simultaneously drawing said frames together and moving said roll into extended position.

4. A machine of the kind described comprising a lower frame, a roll journalled

therein, a second frame pivotally secured to the first frame, a roll carried by the first frame adapted to press against the first roll, a tension roll supported by the lower frame and means for simultaneously connecting said frames together and moving said roll into extended position.

5. A machine of the kind described comprising a frame, a roll journalled therein, a second frame pivotally secured to the first frame, a roll carried by the second frame against the first roll, an eccentric on the first frame, a hook journalled on said eccentric adapted to hold the free end of the second frame in engagement with the first frame and means for turning the eccentric to draw the hook downwards.

6. A machine of the kind described comprising a lower frame, a roll journalled therein, a second frame pivotally secured to the first frame, a roll carried by the second frame adapted to press against the first roll, a hook adapted to hold the free end of the second frame in engagement with the first frame, a shaft, arms on said shaft, a tension roll carried by said arms and means for simultaneously moving said shaft and connecting and disconnecting said hook.

7. A machine of the kind described including a shaft, arms on said shaft, a tension roll carried by said arms, a toggle joint for releasably holding the tension roll in operative position, an adjustable coupling between said shaft and said toggle joint, and a graduated quadrant adjacent said arms to determine the desired point of adjustment of said coupling.

8. A machine of the kind described comprising a lower frame, a roll journalled therein, an upper frame pivotally secured to the lower frame, a roll carried by the upper frame, means for releasably holding the upper and lower frames together, a table secured to the lower frame extending forwardly from the first mentioned roll, a roll journalled adjacent the front edge of said table, a roll journalled in the lower rear portion of said lower frame, a shaft journalled in the lower frame, arms on said shaft and a tension roll carried by said arms.

In testimony whereof I have hereunto subscribed my name.

KENWORTHY J. THOMPSON.
